W. T. SMITH.
CHENILLE FABRIC.

No. 20,371.

Patented Dec. 9, 1890.

UNITED STATES PATENT OFFICE.

WILLIAM T. SMITH, OF PHILADELPHIA, PENNSYLVANIA.

DESIGN FOR A CHENILLE FABRIC.

SPECIFICATION forming part of Design No. 20,371, dated December 9, 1890.

Application filed November 4, 1890. Serial No. 371,142. Term of patent 3½ years.

To all whom it may concern:

Be it known that I, WILLIAM T. SMITH, a citizen of the United States, residing at Philadelphia, in the county of Philadelphia and State of Pennsylvania, have invented and produced a new and original Design for a Woven Chenille Fabric, Curtain, Table-Cover, or Rug, of which the following is a specification, reference being had to the accompanying photographic print, forming a part thereof, which conveys to any one skilled in the art of chenille-weaving a clear understanding

of the same, and is sufficient to enable such persons to use my invention.

What I claim as my invention, and desire to secure by Letters Patent, is—

The design for a woven chenille fabric, consisting of the ornamentations shown in the photographic print accompanying this specification.

W. T. SMITH.
